CLAIM

The ornamental design for cabinet handle, as shown and described.

DESCRIPTION

FIG. 1 is a front elevational view of a cabinet handle showing our new design;

FIG. 2 is a side elevational view, the opposite side is a mirror image;

FIG. 3 is a front elevational view of a second embodiment of a cabinet handle showing our new design, the size being the only difference; and,

FIG. 4 is a side elevational view, the opposite side is a mirror image.

Portions of FIGS. 1-4 that are shown as broken lines are for illustrative purpose only and form no part of the claimed design.
